UNITED STATES PATENT OFFICE.

WILLIAM H. NOELTING, OF EVANSVILLE, INDIANA, ASSIGNOR TO FAULTLESS CASTER COMPANY, OF EVANSVILLE, INDIANA, A CORPORATION.

ANGLE-IRON BRACKET AND SLIDE.

Application filed July 17, 1923. Serial No. 652,062.

To all whom it may concern:

Be it known that I, WILLIAM H. NOELTING, a citizen of the United States, and a resident of Evansville, county of Vanderburgh, and State of Indiana, have invented a certain new and useful Angle-Iron Bracket and Slide; and I do hereby declare that the following is a full, clear, and exact description thereof, reference being had to the accompanying drawings, in which like numerals refer to like parts.

This invention relates to slide constructions for legs on furniture and household appliances.

The chief object of this invention is to simplify the construction of slides which heretofore have been used. These slides have been of two types, one a discus shaped construction provided with a stem or pintle which was yieldingly and detachably supported by a standard caster socket. The other type of slide construction included a button head portion rigid with a support, in turn rigidly and relatively permanently secured to the leg of the household appliance or furniture article. For washing machines and the like, it is frequently desirable to utilize two casters and two slides upon a four legged machine. Likewise in the manufacture of furniture and household appliances to secure a relatively firm and stationary support, it is the practice to provide slides upon the legs thereof, which slides permit the workmen to work upon said furniture or appliances without the latter slipping or sliding during such working. Thereafter the slides are removed and replaced by casters. Such a procedure also preserves the ends of the legs.

The chief feature of the invention consists in the accomplishment of the foregoing object by constructing a bracket slide which is adapted to be clampingly engaged upon a multi-sided non-tubular leg, which slide construction includes a slide portion integral with the clamping portion.

The full nature of the invention will be understood from the accompanying drawings and the following description and claims.

In the drawings, Fig. 1 is a top plan view of one form of unitary slide and bracket applied to an angle iron leg, the latter being shown in section. Fig. 2 is an elevational view of the same. Fig. 3 is a

view similar to Fig. 1 of a modified form of the invention. Fig. 4 is an elevational view of the modification shown in Fig. 3. Fig. 5 is a view similar to Fig. 1 of another modified form of the invention. Fig. 6 is 60 an elevational view of the modification shown in Fig. 5. Fig. 7 is a view similar to Fig. 1 of a modified form of the invention. Fig. 8 is an elevational view of the modification shown in Fig. 7. Fig. 9 is a view 65 similar to Fig. 1 of another modified form of the invention. Fig. 10 is an elevational view of the modification shown in Fig. 9. Fig. 11 is a view similar to Fig. 1 of a modified form of the invention. Fig. 12 is an 70 elevational view of the modification shown in Fig. 11. Fig. 13 is a view similar to Fig. 1 of another modified form of the invention. Fig. 14 is an elevational view of the modification shown in Fig. 13. Fig. 15 is a view 75 similar to Fig. 1 of a modified form of the invention. Fig. 16 is an elevational view of the modification shown in Fig. 15. Fig. 17 is a view similar to Fig. 1 of another modified form of the invention. Fig. 18 is an 80 elevational view of the modification shown in Fig. 17. Fig. 19 is an enlarged central sectional view through the slide and a portion of the base of the combination bracket and slide. Fig. 20 is a view similar to Fig. 85 19 and of a modified form of slide and base. Fig. 21 is a view similar to Fig. 19 and of a modified form of slide and base. Fig. 22 is a view similar to Fig. 19 and of a modified form of slide and base. Fig. 23 is a view 90 similar to Fig. 19 and of a modified form of slide and base.

In the drawings there is herein illustrated a multi-sided non-tubular leg which herein is illustrated as of angle formation and is 95 shown as the conventional angle iron having the sides 30 and 29 joined at 28 and having the bottom edge 27 and the side edges 26.

The combination bracket and slide is herein illustrated in Figs. 1 and 2 as formed of 100 a base 31 which supports a slide portion 32 and between said slide portion and said base there is preferably provided a reinforcing ring 33. In Figs. 1 and 2 the base 31 supports a pair of outwardly projecting ledges 105 which are upturned as at 34, and these ledges are lipped as at 34^a. Likewise, the base 31 supports a back 35, which back 35 is provided with laterally extending flanges 36 that pass around the edge 26 of the angle 110

iron leg; and as shown by the dotted line 36^a, said flanges are inclined slightly to secure a wedging action when positioned upon the angle iron leg. Said flanges 36 are also 5 slightly turned at their ends, as indicated at 36^b to increase the clamping action and facilitate the application of the slide to the leg.

Throughout the description and in the 10 drawings substantially similar numerals will indicate substantially similar parts in the several figures illustrating the modified forms of the invention, said numerals, however, being increased by 100 in each instance. 15 Since the angle iron leg is shown substantially the same in each figure, for the purposes of this description the same numbers will be applied to the same parts of the leg in the several figures. In Figs. 3 and 4 20 a modified form of the invention is illustrated, and herein said modified form of the invention includes the base 131, slide 132, and the reenforcing ring 133, as well as the back 135. Herein the back 135 and base 131 25 are extended and form a cup 137 adapted to receive and seat the end of the angle iron leg. Positioned above the cup and in substantially parallel relation there is a band 138 which is a continuation of the back 30 135, which construction is shown clearly in Fig. 3. In Fig. 5 a modified form of the invention shown in Figs. 1 to 4 inclusive is illustrated, and herein the base 231 supports as usual the slide 232 reenforced by the ring 233. The back 235 and the base 231 are 35 extended to form the cup 237 substantially similar to the cup 137 illustrated in Figs. 3 and 4. The back 235 likewise is extended at 236 to form clamps substantially similar 40 to the clamps 36 shown in Figs. 1 and 2. In Figs. 7 and 8 another form of the invention is illustrated which is a modification of that shown in Figs. 1 to 4 inclusive. Herein the base 331 supports the back 335 45 and the upwardly extending flanges 334 which are lipped as at 334^a. The band 338 is supported by the back 335 in substantially the same manner as illustrated in the form of the invention shown in Figs. 3 and 4.

In Figs. 9 and 10 a further modified form 50 of the invention is illustrated, and in this form of the invention the base 431 supports the slide 432 reenforced by the ring 433. The base 55 also supports the upstanding clamping flanges 434 lipped as at 434^a, said flanges being substantially similar to those shown in Figs. 1 and 2. The back 435 herein not only supports the band 438 substantially similar to the band 138 shown in Figs. 3 and 4, but also supports the lateral clamping flange or projection 436 substantially similar to the flange 36 shown in Figs. 1 and 2, and as likewise illustrated in said 60 figures, the flange 436 is inclined at 436^a to secure a wedging action and having its free 65

turns or lipped at 436^b to increase the clamping action.

In Figs. 11 and 12 a modified form of the invention is illustrated, and in this form of the invention, the base 531 supports the usual slide 532 reenforced by the ring 533. The base also supports the upstanding flanges 534 having their free ends turned as at 534^a to increase the clamping action and 70 permit the ready application of the bracket to the angle iron leg. The base 531 also supports the back 535, and projecting from said back but adapted to engage the opposite side of the leg from that engaged by the adjacent upstanding flange 534 is a flange 539, the free end of which is turned at 539^a to permit the ready application of the bracket to the leg. Although not herein 75 illustrated the portions 539, instead of being 80 a continuation or struck from the back 538 as illustrated and will be described subsequently, may be struck from the base and extended upwardly without departing from the broader features of this invention. 85

In Figs. 13 and 14 a further modified form of the invention is illustrated, and in this form the base 631 supports the usual slide 632 reenforced by the usual ring 633. The base 631 likewise supports the back 635 90 which is extended at 636 to form the usual lateral clamping flanges similar to the flanges 36 shown in Figs. 1 and 2, which flanges are inclined as indicated at 636^a, and the free ends of which are turned as indicated at 636^b.

In Figs. 15 and 16 a modified form of the invention is illustrated, and in this form of the invention the base 731 supports the usual slide 732 reenforced by the usual ring 105 733. The base 731 also supports the cup 737 and the back 735. Herein the back is shown apertured as at 739^b to provide a flange 739, the free end of which is turned as indicated at 739^a to permit of ready application of the bracket to the leg. 110

In Figs. 17 and 18 there is illustrated a further modified form of the invention, which from inspection it will be noted, includes the several basic features illustrated 115 in the preceding figures previously described. In this form of the invention the base 831 supports the usual slide 832 reenforced by the usual ring 833. The base 831 in addition thereto supports the cup 120 portion 837 and extending upwardly from said cup portion is the usual upwardly extending flange 834 having its free end turned as at 834^a. The base 831 also supports the back 835, and supported by said 125 back and as an extension thereof is the band 838. Also supported by the back 835 and extending therefrom is the lateral clamping flange 836 inclined as at 836^a to 130 secure a wedging action and having its free

end turned as at 836^b to increase the clamping action.

In all of the preceding figures the slide construction has been conventionally illustrated and designated by the numerals 32 and 33 preceded by the appropriate designation corresponding to the figure illustrated.

Reference will now be had to Figs. 19 to 23 wherein the various forms of slides are illustrated. In Fig. 19 the base 31 is shown supporting a slide 32, which slide is integral with said base 31 and is curved to form a cup. In Fig. 20 the base 31 is shown supporting the slide or cup 32, and interposed between the base and the slide or cup 32 is the reenforcing ring 33, which ring and slide are integral with the base 31.

In Figs. 21 to 23 inclusive the slide construction is shown as a separate portion from the base, but supported and retained thereby. In Fig. 21 the base 931 is provided with a ring portion downwardly turned and indicated by the numeral 933 and integral with said base. The ring portion 933 is apertured as at 940, and positioned in said aperture 940 is the slide 942 which may be of rubber, wood, felt or any other suitable material. The slide 942 is provided with a peripheral groove 943 adapted to receive the supporting ring 933 and the head portion 944 is adapted to retain the separable slide 942 upon the supporting ring and base 933 and 931 respectively.

In Fig. 22 a modified form of the invention is illustrated and herein the base 951 is provided with the usual reenforcing ring 952, cup-like in formation, and provided with a central opening 960. The separable slide 962 of suitable material such as previously described is reduced as at 963 so as to be seatable in the central opening 960. The extended portion 964 of said separable slide 962 is provided with an annular groove 965, and said annular groove is adapted to receive a split clamping spring ring 966 to retain said detachable slide 962 upon said base 951.

In Fig. 23 a modified form of slide construction is illustrated, and herein the base 971 includes a supporting and reenforcing ring 973. Herein the base 971 is extended to form an inverted cup, as at 974, and positioned in said cup is a suitable slide 982 having a locking portion 983 seatable in the cup thus formed.

While the invention has been described in great detail in the foregoing specifications and illustrated with equal detail in the drawings, the same is to be considered as illustrative and not restrictive in character. The various modifications herein illustrated and described, as well as those suggested, and those which will readily sug-

gest themselves to those persons skilled in the art are all considered to be within the broad purview of this invention as outlined by the appended claims, all of which read upon Figs. 17 and 18.

The invention claimed is:

1. A slide for multi-sided non-tubular legs comprising a bracket for clampingly engaging said leg to yieldingly retain the same thereon, a base integral with the bracket, a slide including a curved portion, and a reenforcing ring interposed between said curved portion and said base, said ring being integral with said base.

2. A slide for multi-sided non-tubular legs comprising a bracket for clampingly engaging said leg to yieldingly retain the same thereon, a base integral with the bracket, a slide including a curved portion, and a reenforcing ring interposed between said curved portion and said base.

3. A slide for multi-sided non-tubular legs comprising a bracket for clampingly engaging said leg to yieldingly retain the same thereon, a base integral with the bracket, and a slide including a curved portion, and a reenforcing ring interposed between said curved portion and said base, said ring and said curved portion being integral with said base.

4. A slide for multi-sided non-tubular legs comprising a base, a slide rigid with said base and supported thereby, a cup secured to said base and adapted to envelope the end of the leg for clampingly securing the slide to the leg, and an upstanding clamp secured to said base for clampingly engaging the exterior of the leg for securing the slide to the leg.

5. A slide for multi-sided non-tubular legs comprising a base, a slide rigid with said base and supported thereby, a cup secured to said base and adapted to envelope the end of the leg for clampingly securing the slide to the leg, and a lateral clamp secured to said base for clampingly securing the slide to the leg.

6. A slide for multi-sided non-tubular legs comprising a base, a slide rigid with said base and supported thereby, a cup secured to said base and adapted to envelope the end of the leg for clampingly securing the slide to the leg, and a band for enveloping the leg above the base and secured thereto for clampingly securing said slide to said leg.

7. A slide for multi-sided non-tubular legs comprising a base, a slide rigid with said base and supported thereby, an upstanding clamp secured to said base for clampingly securing the slide to the leg, and a band for enveloping the leg above the base and secured thereto for clampingly securing said slide to said leg.

8. A slide for multi-sided non-tubular legs comprising a base, a slide rigid with said

base and supported thereby, a lateral clamp secured to said base for clampingly securing the slide to the leg, and a band for enveloping the leg above the base and secured thereto for clampingly securing said slide to said leg.

9. A slide for multi-sided non-tubular legs comprising a base, a slide rigid with said base and supported thereby, a cup secured to said base and adapted to envelope the end of the leg for clampingly securing the slide to the leg, an upstanding clamp secured to said base for clampingly securing the slide to the leg, and a lateral clamp secured to said base for clampingly securing the slide to the leg.

10. A slide for multi-sided non-tubular legs comprising a base, a slide rigid with said base and supported thereby, a cup secured to said base and adapted to envelope the end of the leg for clampingly securing the slide to the leg, an upstanding clamp secured to said base for clampingly securing the slide to the leg, and a band for enveloping the leg above the base and secured thereto for clampingly securing said slide to said leg.

11. A slide for multi-sided non-tubular legs comprising a base, a slide rigid with said base and supported thereby, a cup secured to said base and adapted to envelope the end of the leg for clampingly securing

the slide to the leg, a lateral clamp secured to said base for clampingly securing the slide to the leg, and a band for enveloping the leg above the base and secured thereto for clampingly securing said slide to the leg.

12. A slide for multi-sided non-tubular legs comprising a base, a slide rigid with said base and supported thereby, an upstanding clamp secured to said base for clampingly securing the slide to the leg, a lateral clamp secured to said base for clampingly securing the slide to the leg, and a band for enveloping the leg above the base and secured thereto for clampingly securing said slide to the leg.

13. A slide for multi-sided non-tubular legs comprising a base, a slide rigid with said base and supported thereby, a cup secured to said base and adapted to envelope the end of the leg for clampingly securing the slide to the leg, an upstanding clamp secured to said base for clampingly securing the slide to the leg, a lateral clamp secured to said base for clampingly securing the slide to the leg, and a band for enveloping the leg above the base and secured thereto for clampingly securing said slide to said leg.

In witness whereof, I have hereunto affixed my signature.

WILLIAM H. NOELTING.
